US00D616600S

(12) **United States Design Patent**
Gilbert et al.

(10) **Patent No.:** **US D616,600 S**
(45) **Date of Patent:** **** May 25, 2010**

(54) **LIGHT FIXTURE**

(75) Inventors: **Christopher Jon Gilbert**, Moreland Hills, OH (US); **Lawrence Morris Bibi**, Woodcliff Lake, NJ (US); **Min S. Kim**, Jersey City, NJ (US)

(73) Assignee: **Moen Incorporated**, North Olmsted, OH (US)

(**) Term: **14 Years**

(21) Appl. No.: **29/346,840**

(22) Filed: **Nov. 6, 2009**

(51) **LOC (9) Cl.** **26-99**

(52) **U.S. Cl.** **D26/155**

(58) **Field of Classification Search** **D26/145, D26/154, 155, 142, 118, 138, 120, 92, 87, D26/71, 67, 60, 62, 63, 68, 70, 72, 80, 81, D26/85, 86, 88, 113, 140, 141, 143, 144, D26/153; D25/126, 127; 52/28, 295; 362/432, 362/443, 800, 431, 153, 153.1, 395, 401, 362/405, 410; D23/238, 239, 240, 241, 242, D23/243, 244, 245, 247, 249, 255**

(57) **CLAIM**

The ornamental design for a light fixture, as shown and described.

DESCRIPTION

FIG. 1 is a perspective view of a light fixture of the new design;

FIG. 2 is a front elevational view of the light fixture;

FIG. 3 is a rear elevational view of the light fixture;

FIG. 4 is a left side elevational view of the light fixture, the right side elevational view being a mirror image thereof;

FIG. 5 is a top plan view of the light fixture;

FIG. 6 is a bottom plan view of the light fixture;

FIG. 7 is a front elevational view of the light fixture showing an additional light fixture in broken lines;

FIG. 8 is a front elevational view of the light fixture showing two additional light fixtures in broken lines; and,

FIG. 9 is a front elevational view of the light fixture showing three additional light fixtures in broken lines.

The broken lines shown in the drawings are included to illustrate environmental structures and form no part of the claimed design.

1 Claim, 8 Drawing Sheets
